UNITED STATES PATENT OFFICE.

CHRISTIAN FADUM, OF BROOKLYN, NEW YORK.

SAFETY ATTACHMENT FOR MOLD-LINERS FOR TYPE-SLUG-CASTING MACHINES.

1,282,556.

Specification of Letters Patent. Patented Oct. 22, 1918.

Application filed May 25, 1917. Serial No. 170,806.

To all whom it may concern:

Be it known that I, CHRISTIAN FADUM, a citizen of the United States, and a resident of the city of New York, borough of Brooklyn, in the county of Kings and State of New York, have invented a new and Improved Safety Attachment for Mold-Liners for Type-Slug-Casting Machines, of which the following is a full, clear, and exact description.

Among the principal object which the present invention has in view are: to avoid damage to liners used for varying the length of the slug casting mold used in machines of the character mentioned; to avoid delay in the operation of the machine incident to the stoppage and repair caused by damage done to a liner; and to perfect the mechanism for arresting the operation of the casting machines when the ejectors do not correspond with the slug cast.

Drawings.

Figure 1 is a front elevation of the mold disk of a type slug casting machine and of a portion of the ejector mechanism usually provided therefor, and a safety attachment constructed and arranged in accordance with the present invention;

Fig. 2 is an edge view of said disk, showing in conjunction therewith portions of said safety attachment and fragments of the ejector blades commonly used in machines of the character mentioned, the safety attachment being shown in its normal inactive position;

Fig. 3 is a similar view showing portions of the safety attachment in their active positions;

Fig. 4 is a detail view showing fragments of the mold disk and ejector blades therefor, together with elements of the safety attachment showing the same in their active positions;

Fig. 5 is a similar view showing the elements of the safety attachment in their inactive positions;

Fig. 6 is a plan view of the latch mechanism of the safety attachment herein disclosed;

Figs. 7, 8 and 9 are views diagrammatically arranged for showing the relation of the tripping mechanism, the liners used in conjunction therewith, the casting mold space, and the ejector blades for clearing the same.

Fig. 10 is a perspective side view of the mold and ejecting devices, with parts broken away to show the interior structure.

Description.

Type slug casting machines of the character illustrated in the accompanying drawings, have a rotary mold-carrying disk, such as indicated by the designating numeral 15. Secured rigidly to the face of the disk is a series of mold blocks 16. The molds 17 formed in the said disk are varied in length to suit the work to be performed by inserting from one end of each mold a liner 18.

Referring to Fig. 1 of the drawings, attention is drawn to the fact that when operating only one mold of those assembled on the disk 15 is employed at one time. The casting position of the mold is at the upper end of the vertical diameter of the disk.

After the slug is cast, the disk 15 rotates contra-clockwise, as indicated by the arrow in Fig. 1, three-fourths of a complete revolution, to the ejecting position at the right of the horizontal diameter of said disk. The operation of the present mechanism occurs when the mold is in the ejecting position.

The operation primarily releases the clutch of the driving mechanism, which is connected to the clutch rod 19 of the driving mechanism of the machine. This rod is best seen in Figs. 2 and 3 of the drawings. The rod 19 is thrust from the normal position shown in Fig. 2 of the drawings, to the clutch-releasing position shown in Fig. 3 of the drawings by the trip lever 20. The lever 20 is so rocked when the blade 21 is lifted into the path of a reciprocating plunger 22. The plunger 22 is reciprocatively mounted in a housing 23 stationarily disposed on the frame of the machine. Normally, the plunger 22 is retracted by the spring 24, as seen in Fig. 2 of the drawings. As the disk 15 is brought forward, the plunger 22 is projected thereby to the position shown in Fig. 3 of the drawings. If at this time the blade 21 is in its normal depressed position, the head of the plunger 22 passes over the same without rocking the lever 20 and without releasing the clutch of the casting machine.

The blade 21 above mentioned is in the path of the plunger 22 whenever the spring 25, shown best in Fig. 1 of the drawings, is permitted to elevate the arm 26 and the link 27 connecting said arm and said blade.

Normally, the elevation of the arm 26 and

parts connected therewith is prevented by the interposition of the knife edge 28 extended from the side of a slide 29. The knife edge 28 normally rests on the knife edge 30 extended from the upper side of the arm 26. The slide 29 has a face plate 31, over which moves the head 32 of an adjustment arm 33. Normally the slide 29 and the face plate thereof is pressed against the head 32 and the wearing point 34 thereof by a compression spring 35 (see Fig. 2 of the drawings).

The arm 33 is adjusted in service in correspondence with the movement of the blade lever 36. The blade lever 36 is a part of the mechanism hereinafter employed for determining the number of ejector blades employed for ejecting the slug from the mold. To this end the upper end of the blade lever 20 36 is provided with numbers intended to denote the length of slug designed to be cast and the width of the ejector blades 37 employed for ejecting the slug. The length of the slug is determined by the liner employed. 25 The liner is presumed to correspond with the length of the slug or line of type represented thereby and as indicated by the numeral exposed through the peep-hole in the frame of the linotype machine. As seen in the drawings, Fig. 1, this peep-hole shows the numeral 12, which indicates to the operator that the line to be cast is of a 12-m length. Difficulties have arisen from the fact that through carelessness or indifference, the liner 30 which is placed in the mold does not correspond with the adjustment of the mechanism connected with the blade lever 36, or, in other words, the liner placed in the mold may provide for a 10-m length of slug though 35 the mechanism is set for a 12-m length of slug. Consequently the liner and mechanism connected therewith, or the ejector mechanism, interferes with the result that the one or other is destroyed. To illustrate a usual 40 form of ejector mechanism, there is shown in Fig. 10 of the drawings, the mechanism illustrated in a former Patent, No. 1,099,448, issued June 9, 1914.

It will be understood that any other suitable mechanism to selectively control the ejector blades may be employed.

In the mechanism shown in said Fig. 10 of the drawings, the lever 48 is employed to lift the blade 36. A quadrant 49 and grip-release latch 50 are employed for holding the lever 48 in adjusted position. The handle 51 of the lever extends to the front of the machine adjacent the operator's working station and is manipulated by him to lift and 55 depress the slide 53. A guide bar 56 extended laterally from the side 53, supports in sliding relation thereto a plunger 54. The plunger 54 is suitably connected with a reciprocating head 57 and extends into the 60 path of lugs 55 set out from the side of the

blades or mechanism directly controlling the same. It will be understood that when the mechanism for controlling the plunger 54 corresponds with the liner 18, the linotype machine functions properly and only at such 70 times.

In the present attachment, the lever 36 and the selector arm 38 thereof are connected with the arm 33 by means of a plunger 39, bell crank lever 40, and links 41 and 42. The 75 plunger 39 is suitably guided in its operation in bearings mounted in the frame of the casting machine.

The movement imparted by the lever 36 to the selector arm 38 is increased or diminished, as the case may be, to provide movement of the arm 33 of an ascertained ratio to the blades 37 and mechanism for introducing or retiring said blades from active positions. The total length of travel of the arm 33 and 80 head 32 thereof, corresponds with the difference in the length of the minimum or maximum extensions of the tail-pieces 43 with which each of the liners 18 in the present invention is provided. The tail-pieces 43 extend beyond the molds 16 to a plane parallel with and normally juxtaposed to the plane of the lower edge of the head 32. 85

If by mistake the lever 36 and mechanism connected therewith is not operated to arrange the blades 37 in correspondence with the liner 18, the head 32 will extend below the upper end of the tail-piece 43 of the liner 18. 90

When, now, the disk 15 and the mold 16 100 in which the liner 18 is disposed, makes its first movement forward, the end of the tail-piece 43 engages the head 32 and forces the same backward against the plate 31 and slide 29 thereof. The arm 33 is permitted to 105 move, being pivotally mounted in bearings 44, as shown best in Figs. 1 and 2 of the drawings.

When the tail-piece 43 of any liner 18 thus moves the head 32 and slide 29, the knife 110 edge 28 of the said slide passes out of engagement with the knife edge 30 to be held against subsequent retraction by the spring 35. When the disengagement between the two knife edges occurs as stated, the spring 115 25 lifts the arm 26 and through the connection, by means of the link 27, lifts the blade 21 into engagement with the plunger 22. When the disk 15 subsequently moves back, the spring 25 is permitted to fully lift the 120 blade 21 into the path of, to be engaged by, the plunger 22.

When now the disk 15 again moves forward preliminarily to the movement of the blades 37 for the ejection of the slug, the 125 plunger 22 engages the blade 21 and rocks the lever 20 to move the clutch rod 19, to the end that the clutch is released and the casting machine arrested in its movement prior to bringing forward the blades 37. 130

this manner the damage so often occurring to the liners, molds and ejector blades, due to carelessness or inattention on the part of the operator in setting the blade-adjusting mechanism, is avoided.

To permit the employment of two or more molds and to avoid the necessity of removing the liners from the temporarily abandoned mold, I provide means for preventing the operation of the clutch-releasing mechanism, by the tail-piece 43 of the liner in the disused mold. This mechanism consists primarily of a plunger rod 45, which, as is seen best in Fig. 1 of the drawings, is disposed in the path of a lug 46 on the elevator 47. When the elevator is depressed, the used mold 16 is in the casting position at the top of the disk. At this moment, the disused mold might be in the ejecting position at the right of the disk, and the tail-piece 43 of the liner 18 in the disused mold might be in position to trip the clutch-releasing mechanism herein disclosed. To avoid this, the lug 46 engages the plunger rod 45 and holds the arm 26 from being lifted by the spring 25 when the slide 29 is pressed back. In this manner the blade 21 is prevented from rising into the path of the plunger 22. Also the knife edge 30 is held out of the return path of the knife edge 28 and the slide 29 is therefore permitted to resume its original normal position when the disk 15 is retracted. It is obvious that the operation of the elevator 47 and lug 46 upon the plunger 45, occurs only during the period of casting the line, and does not interfere with the operation of the herein described safety attachment when the mold being used is in the slug-ejecting position.

Claims.

1. The combination of a type casting machine adapted for performing a series of successive functions; casting molds therefor; liners insertible in said molds for vary-

ing the same; a stopping mechanism for arresting the operation of said casting machine; and means for operating said stopping mechanism, said means embodying the liners of said molds, said means embodying extensions on said liners, said extensions being disposed in service exterior to said molds.

2. The combination of a type casting machine having a variable length casting mold, a driving mechanism, a multiple blade ejector operatively connected with said driving mechanism, and a mechanism for adjusting said ejector in correspondence with the various lengths of said mold; with a series of liners for said mold constructed in accordance with the various lengths thereof, said liners having tail-pieces extending beyond said mold in correspondence with the line to be cast in said mold; and stopping mechanism for said machine adapted to be operatively engaged by said tail-pieces preliminarily to the operation of said ejector.

3. The combination of a type casting machine having a variable length casting mold, a driving mechanism, a multiple blade ejector operatively connected with said driving mechanism, and a mechanism for adjusting said ejector in correspondence with the various lengths of said mold; with a series of liners for said mold constructed in accordance with the various lengths thereof, said liners having tail-pieces extending beyond said mold in correspondence with the line to be cast in said mold, and stopping mechanism for said machine adapted to be operatively engaged by said tail-pieces preliminarily to the operation of said ejector, said stopping mechanism embodying an interference member movable in correspondence with the adjustment of said ejector blades and adapted for interposition in the path of said tail-pieces when said blades exceed the length of the mold.

CHRISTIAN FADUM.
